UNITED STATES PATENT OFFICE.

ARTHUR J. MASON, OF HOMEWOOD, ILLINOIS.

ART OF SAND WASHING.

Application filed April 19, 1928. Serial No. 271,235.

This invention relates to improvements in the art of sand washing and is here shown as the same may be practiced to separate any sandy material from a stream of water. For example, the invention may be used to separate phosphate sand from the mud and water in a flowing flume or stream.

By the methods as heretofore practiced, such separation was effected by slowing down the movement of the stream to a point at which it carries off the lighter mud and precipitates the heavier sands. Such older methods, however, have been unsatisfactory, since they require a great deal of clean water and also eventually trap much undesirable mud.

One of the features of my invention is the elimination of the undesirable features of the methods as heretofore practiced.

It is well known that in hydraulic dredging, fine sands settle in the conductive pipes, if they are sufficiently long, even where the stream has a velocity of fifteen feet a second. This is due to the friction of the sand dragging along the bottom of the pipe, aided by the packing of the fine pieces between the larger ones, forming a clean, hard dense deposit of sand finally choking the pipes. Such deposit of sand may also be attributed to the skin friction between the water and the wall of the pipe causing a slowing of the current adjacent the wall, thus causing a deposit of sand against the wall. In this manner, the deposit of sand builds up until the pipe becomes nearly choked. I employ this principle in carrying out my invention.

In that form of device embodying the features of my invention shown in the accompanying drawings, Figure 1 is a perspective view, Fig. 2 is a view as indicated by the line 2 of Fig. 1, Fig. 3 is a partial sectional view, and Fig. 4 is a similar view showing the parts in altered position.

As shown in the drawings, A indicates in general an inclined box or flume with the side walls 10 and bottom 11. B indicates the supply pipe through which the mixed water and sand are fed into the header or manifold 12 at the head of the flume. The header

12 is provided with outlets 13 so arranged in number and size that the stream will spread itself substantially evenly across the entire width of the bottom 11. The inclination of the flume and rate of supply may be so that the stream will be substantially one-quarter inch deep in the flume.

In order to prevent channeling, that is, to prevent the water from flowing unevenly on the bottom of the flume and favoring certain channels, where it would scour away sand previously deposited, I may provide a plurality of vertical parallel longitudinally arranged partitions or strips 14, 14 serving to divide the entire width of the flume into a plurality of channels 15 of substantially equal width. The dividing strips 14 are joined together by means of cross bars 16 to form a rigid frame which in turn may be suspended from above by means of a rope 17 and counterbalanced by a weight 18. By this construction the strips 14, 14 may be raised or lowered. At the commencement of the operation the strips rest upon the bottom and are raised from time to time until the flume is full. They preferably are raised from time to time so that their lower edges are a short distance below the surface of the accumulating deposit of sand, as shown in Fig. 4.

I have found, that at the lower end of the flume there may be deposited certain lighter undesirable particles which may be segregated and rejected. These lighter particles are deposited near the end of the flume because they have a lower specific gravity and a rough flaky form.

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art.

What I claim is new, and desire to secure by Letters Patent, is:

1. A separating flume with longitudinally arranged vertical partitions spaced to form narrow elongated separating channels in the flume, and means for adjustably controlling the vertical position of the partitions.

2. A separating flume with longitudinally arranged vertical partitions spaced to form narrow elongated separating channels in the

flume, said partitions being joined together by cross members to form a rigid unitary structure, and means for adjustably controlling the vertical position of said structure. 10

In witness whereof, I have hereunto set my hand this 7th day of April, 1928.

ARTHUR J. MASON.
